TRAFFIC SIGNALING SYSTEM

Clarence E. Lemax, Oak Park, Ill., assignor to
Associated Electric Laboratories, Inc., Chicago,
Ill., a corporation of Delaware

Application October 31, 1938, Serial No. 237,898

10 Claims. (Cl. 177—337)

The present invention relates to signaling systems and more particularly to improvements in highway traffic signaling systems wherein traffic control signaling devices located at one or more highway intersections along a highway or street are controlled from a master control station over a line interconnecting the master control station and signaling device switching units located at the respective traffic lane intersections.

In signaling systems of the character noted, the plurality of signaling devices located at each traffic intersection conventionally comprises a plurality of groups of lamps, each group including red, green and amber signal lamps positioned to face in one traffic approach direction, thereby to give universally recognized indications to approaching motor vehicle operators or pedestrians. In a four-way intersection, four such groups of lamps are usually provided for properly signaling in each of the four traffic approach directions. The lamps at each intersection are arranged automatically to be controlled by the apparatus embodied in an associated control box or switching unit, which apparatus functions to energize the lamps in a definite cyclic order. Thus, on a north-south, east-west intersection, the north-south right of way signal lamps are energized for a portion of each operating cycle concurrently with the east-west stop signals. During another portion of each operating cycle, the north-south stop signals are energized concurrently with the east-west right of way signals. Between the respective portions of each operating cycle during which traffic right of way is allotted to the respective intersecting traffic lanes are periods conventionally known as change-over intervals during which the amber or caution signals are alone energized or are energized in conjunction with the right of way or stop signals. A complete operating cycle of the group of lamps at any intersection includes, therefore, the two periods respectively giving right of way to the two intersecting traffic lanes and two change-over periods. Usually the operating cycles of the signaling devices located at the various intersections are related in a particular manner such that the most expeditious movement of heavy traffic on all intersecting traffic lanes is achieved. The desired relation between the signaling device operating cycles is accomplished by operating the switching apparatus or signaling device control switches embodied in the various switching units in synchronism. With the usual arrangement if a fault develops in the apparatus provided at the master

control station or in the line circuit interconnecting the master control station and the various switching units, the signaling device control switches respectively embodied in the switching units cease to operate. As a result the cyclic operation of the signaling devices is arrested and all of the signaling devices are deenergized or the last energized signaling devices are maintained energized continuously. In either case the control of the traffic proceeding through each traffic lane intersection is disrupted.

It is an object of the present invention, therefore, to provide an improved signaling system of the general character briefly described above which is so arranged that the cyclic operation of the traffic control signaling devices is not permanently arrested in the event of failure of the control of the associated switching units which is normally exercised over the line circuit interconnecting the switching units and the master control station.

It is another object of the invention to provide for use in a system of the character described an improved switching unit which is operative to cause the cyclic operation of a plurality of associated traffic control signaling devices, is normally controlled over an incoming line circuit from a master control station, and is so arranged that failure of the control normally exercised over the line circuit does not result in a permanent interruption of the cyclic operation of the associated signaling devices.

It is a further and more specific object of the invention to provide a switching unit of the character briefly described which comprises normally inactive auxiliary control apparatus arranged in an improved manner and operative as a local unit to cause the continued cyclic operation of the associated signaling devices in the event of failure of the control normally exercised over the line circuit incoming to the unit.

In the illustrated embodiment of the invention there is provided a master control station which is adapted to control a plurality of switching units respectively provided at the various traffic lane intersections of a main highway over a line circuit extending from the master station to each of the switching units and common to all of the units. Each of the switching units comprises apparatus operative in response to control voltage impressed on the line circuit for controlling the energization of the traffic control signaling devices located at the associated traffic lane intersection in a definite cyclic order. In accordance with the present invention nor-

normally inactive auxiliary control means are provided for causing the above-mentioned control apparatus to operate, together with apparatus operative in the absence of control voltage on the line circuit for initiating the operation of the auxiliary control means. More particularly, the apparatus embodied in each switching unit comprises a switch including contacts, a wiper associated with the contacts, and a motor for driving the wipers over the contacts; together with circuit connections controlled by the movement of the wiper over the contacts for controlling the energization of the associated signaling devices. Each unit further comprises apparatus including a pair of polarized relays for repeatedly completing the operating circuit of the associated switch motor, thereby to cause the motor to drive the wipers over their associated contacts. The two polarized relays are arranged alternately to operate in response to voltage pulses of alternate opposite polarity impressed on the line circuit and so long as the relays are operating in the proper order the auxiliary control means, mentioned above, remains inactive. A control device in the form of a thermal relay, operative in response to a sustained deenergized condition of both of the polarized relays, is provided for initiating the operation of the auxiliary control means. This auxiliary control means, like the two polarized relays, is operative repeatedly to complete the operating circuit for the associated switch motor, whereby the cyclic operation of the associated signaling devices is continued even though the polarized relays are inactive. In accordance with a further feature of the invention, there is also provided in each unit apparatus operative to arrest the operation of the auxiliary control means in response to the application of a predetermined control voltage to the line circuit which is different from that utilized in the normal control of the unit. This apparatus, as embodied in each unit, is also operative to cause the energization of a predetermined one of the signaling devices provided in association with the unit whereby a particular traffic indication is displayed at the controlled intersection.

Further features of the invention pertain to the particular arrangement of the circuit elements whereby the above and additional operating features of the system are attained.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which Figures 1 and 2 illustrate a traffic signaling system having embodied therein the features of the invention as briefly outlined above.

Referring now to the drawings, the system as illustrated comprises a plurality of switching units, one of which is shown in Fig. 2, a master control station, as shown in Fig. 1, and a line circuit 6 comprising three conductors 7, 8 and 9 interconnecting the control station with each of the switching units. Only one of the switching units, namely that located in proximity to and arranged to control the signaling devices at the traffic lane intersection 10, is illustrated in detail, but it will be understood that each of

the other switching units provided at the other traffic lane intersections are identical in character with that illustrated. As shown, the signaling devices at the intersection 10 of the east-west highway 11 and the north-south highway 12 comprise a red signal lamp 13, a green signal lamp 14, and an amber signal lamp 15 arranged to give stop, right of way and caution traffic indications, respectively, to traffic traveling east and west along the highway 11. Also included in the plurality of signaling devices at the intersection 10 are the red, green and amber signal lamps 16, 17 and 18, respectively, which are arranged to govern traffic traveling in the north and south directions along the intersecting highway 12. These signaling devices have operating circuits, traced hereinafter, all of which include bus conductors 19 and 20 extending to opposite terminals of any suitable source of commercial frequency current.

For the purpose of energizing the enumerated signaling devices or lamps in a definite cyclic order there is provided in the switching unit of Fig. 2 a cyclically operating switch indicated generally at 21. This switch comprises three sets of bank contacts 22, 23 and 24 of twenty-four points each and wipers 25, 26 and 27, respectively associated with the contact sets in the order of their enumeration. The enumerated wipers are arranged to be driven by motor means in the form of an alternating current motor schematically indicated at 28. More particularly, the wipers 25, 26 and 27 are carried by and rotatable with a rotary shaft 29 which also carries a ratchet wheel 30 at one end thereof. The motor 28 is provided with a shaft 31 which is arranged to drive a second shaft 32 through an appropriate speed reduction gear mechanism provided in a gear box 34. The shaft 32 carries at one end thereof a cam 35 which is arranged to cause the operation of the ratchet wheel 30 through two steps during each revolution of the shaft 32. More specifically, the cam 35 cooperates with a pawl mechanism comprising a pawl 36 pivoted at 37 on a lever 38, which lever is in turn pivotally mounted at 39 upon any suitable support. The pawl 36 is normally biased into engagement with one of the peripherally disposed teeth of the ratchet wheel 30 through the action of a coil spring 40. The lever 38 is biased into engagement with the periphery of the cam 35 through the action of a coil spring 41. In order to actuate the pawl mechanism, the cam 35 is provided with two camming projections 42a and 42b disposed at 55 diametrically opposite points around its periphery. With this arrangement and during clockwise rotation of the shaft 32 in response to operation of the motor 28, the cams 42a and 42b alternately engage the spring biased lever 38. Thus, when the projection 42a, for example, moves against the lever 38, this lever is pivoted about its axis 39 in a clockwise direction to move the pawl 36 to the right so that the ratchet wheel 30 is rotated a predetermined amount in a clockwise direction. As a result, the wipers 25, 26 and 27 are advanced one step or from engagement with one set of contacts into engagement with the next succeeding set of contacts. Thereafter and when the camming projection 42a rides away from the lever 38, the bias exerted on this lever by the spring 41 pivots the lever in a counterclockwise direction so that the pawl 36 is retracted to its cocked position. During continued rotary movement of the cam 35, the wipers 25, 26 and 27 are driven over the contacts of their respective

associated sets, in the manner just explained, at the rate of two steps for each revolution of the shaft 32.

The motor 28 includes an operating circuit having three branches arranged respectively to be completed by way of the cam actuated switch springs 43a, 43b and 44a, 44b and the wiper 27 of the switch 21. The cams for actuating the indicated springs 43a, 43b and 44a, 44b are mounted for rotation with the stub shaft 32. Thus, there is provided a cam 45 mounted upon the shaft 32 for rotation therewith and having formed therein a camming depression 46 which is arranged to cooperate with the extended reversely bent cam follower portion of the spring 43b. A second cam 47, having formed therein a camming depression 48 arranged to receive the reversely bent cam follower portion of the spring 44b, is provided for operating the springs 44a and 44b. The contact springs 43b and 44b are biased in a direction to disengage their respective associated contact springs 43a and 44a. Hence, when the camming portion of the spring 43b falls into the depression 46 of the cam 45, the two springs 43a and 43b are moved out of engagement. At any other time when the cam follower portion of the spring 43b engages the peripheral surface of the cam 45, the springs 43a and 43b are operated into engagement. Similarly, the spring 44b engages its associated contact spring 44a at all times except when the follower portion of the spring 44b drops into the depression 48 of the cam 47. The depressions 46 and 48 provided in the cams 45 and 47, respectively, are angularly displaced from each other by an angle of 180 degrees and from the diametrically opposite projections 42a and 42b by an angle of approximately 90 degrees. The purpose of this arrangement will be apparent from the following description of the operation of the switching unit.

The two branches of the operating circuit for the motor 28 which respectively comprise the springs 43a, 43b and the springs 44a, 44b are also arranged to be controlled by polarized relays connected to the conductors of the line circuit 6. More particularly, there is provided a polarized relay 60 having armature springs included in the branch circuit comprising the springs 43a, 43b, and a second polarized relay 50 having armature springs included in the branch circuit comprising the cam controlled springs 44a and 44b. The respective windings of the two relays 50 and 60 are connected in series across the line conductors 6 and 9 of the line circuit 6 and are so poled that the indicated relays alternately operate in response to voltage pulses of alternate opposite polarity impressed across the indicated line conductors.

For the purpose of arresting the operation of the switch 21, of deenergizing any energized ones of the signaling devices at the intersection 10, and of energizing the amber or caution signaling devices provided at this intersection, there is also embodied in the switching unit of Fig. 2 a third polarized relay 70 having its winding connected across the line conductors 7 and 8 of the line circuit 6 in series with the winding of a fourth polarized relay 80 and in a manner such that it only operates in response to the application of voltage of a predetermined polarity between the indicated line circuit conductors. The polarized relay 80, on the other hand, is only operative when voltage of the opposite polarity is impressed across the line conductors 7 and 8 and, in conjunction with the switch 21 and the motor 28,

functions to maintain a synchronous relation between the operating cycles of the switch 21 and the other similar switches provided at the other switching units controlled from the master control station of Fig. 1 over the line circuit 6.

In order to change the percentage of each signaling cycle during which traffic right of way is allotted to the respective traffic approach directions, there is also embodied in the switching unit illustrated in Fig. 2, a manually operable switch 82 which is so arranged that normally substantially equal portions of each signaling cycle are allotted for traffic right of way along the highway 12 and along the highway 11. Operation of this switch is effective to decrease the portion of each signaling cycle during which traffic right of way is allotted to the highway 11 and to increase by a corresponding amount the period of each cycle during which traffic right of way is allotted to the highway 12.

In accordance with the present invention there is also embodied in the switching unit illustrated in Fig. 2, normally inactive auxiliary control means indicated generally at 75 for controlling the operation of the switch 21. This auxiliary control apparatus comprises an alternating current motor 76 and means comprising a thermal relay 77 for initiating the operation of the motor 76 in response to a sustained deenergized condition of the two polarized relays 50 and 60. The motor 76 includes a shaft 90 which is arranged to drive a stub shaft 91 through the speed reduction gear mechanism of a gear box 92. The auxiliary control apparatus 75 also includes a pair of cam controlled switches 92 and 93 having embodied therein contact springs connected and arranged alternately to complete the above-described two branches of the operating circuit for the motor 28 which are normally controlled by the polarized relays 50 and 60. More particularly, the switch 92 includes a movable spring 94 having a cam follower portion biased to ride against the peripheral surface of a cam 95 mounted for rotation with the stub shaft 91, and the switch 93 comprises a movable spring 98 having a cam follower portion biased to engage the peripheral surface of a second cam 99 also mounted for rotation with the stub shaft 91. The spring 94 is arranged to engage its associated spring 97 when the portion of greatest radius of the cam 95 engages the cam follower portion of the spring 94. When, however, the shaft 91 is rotated so that the cam follower portion of the spring 94 engages the portion of the cam 95 of reduced radius, the indicated spring is moved out of engagement with the spring 97 and into engagement with the spring 96. In a similar manner the spring 98 included in the switch 93 is normally biased out of engagement with its associated springs 63 and 64. When, however, the portions of the cam 99 of large radius engage the follower portion of the spring 98, this spring is moved into engagement with its associated contacts 63 and 64. As explained in detail hereinafter, the arrangement is such that with the auxiliary control means 75 operating, alternate branches of the operating circuit for the motor 28 are completed during each half revolution of the shaft 91.

Referring now more particularly to the details of the master control station illustrated in Fig. 1, the apparatus provided at this station comprises a cyclically operating rotary stepping switch 100 which is arranged to be operated in accordance with the pulses transmitted from a pulse gen-

erator 101 in synchronism with each of the rotary switches corresponding to and including the switch 21 and embodied in the various switching units which are controlled over the line circuit 6. The rotary switch 100 may be of any standard commercial construction and comprises two sets of bank contacts 102 and 103 of twenty-four points each, wipers 104 and 105 respectively associated with the contact sets 102 and 103, and means comprising a motor magnet 106 and a ratchet and pawl mechanism, not shown, for driving the enumerated wipers over the contacts of their respective associated sets. The pulse generator 101 is arranged to deliver spaced control pulses at two different rates. This generator, which is only diagrammatically shown, may, if desired, take the form of a circuit breaker driven by a synchronous motor through a gear reduction box and arranged intermittently to apply ground potential to the two conductors 107 and 108. In the arrangement illustrated, it is contemplated that the fast pulses shall be applied to the conductor 107 and the slow pulses to the conductor 108. These pulses control the energization of the motor magnet 106 embodied in the switch 100. The switch 100, in turn, functions to apply voltage pulses of alternate opposite polarity between the line conductors 8 and 9 of the line circuit 6. For the purpose of selectively controlling the rate of the pulses delivered to the rotary switch operating magnet 106, there is provided a manually operable switch which includes the switch springs indicated at 109, 110 and 111. In order to interrupt the normal mode of operation of the switching units controlled over the line circuit 6 and to render the units effective continuously to energize the amber or caution signaling devices located at the controlled intersections during the hours when light traffic conditions exist, a second manually operable switch 112 is provided. Current for energizing the operating magnet 106 of the rotary switch 100 is derived from a battery 118. This same current source is also utilized in applying voltage pulses of negative polarity to each of the two line circuit conductors 7 and 9. In order to apply voltage pulses of the opposite polarity to the line conductors 7 and 9, there is provided a second battery 119. In practice the terminals of the battery 118 are connected to two bus conductors to which certain of the circuit conductors are also connected. In a similar manner the terminals of the battery 119 are connected to bus conductors to which others of the circuit connections of the master control station extend. For convenience in describing the circuits, however, the two sources of current have been individually indicated in each instance.

Referring now more particularly to the operation of the apparatus and assuming that the elements of the master control station occupy the positions illustrated in the drawings, the ground pulses applied to the conductor 108 are effective to cause the intermittent energization of the rotary switch operating magnet 106 over a circuit extending by way of the conductor 108, the switch springs 111, 109 and 114 and the winding of the magnet 106 to the negative terminal of the grounded battery 118. Each time this magnet is energized over the circuit just traced, it operates in conjunction with its associated ratchet and pawl mechanism to advance the wipers 104 and 105 one step. With the wiper 104 standing in engagement with its associated first contact, the battery 118 is connected across

the line circuit conductors 8 and 9 of the line circuit 6, the negative terminal of this battery being connected to the conductor 9 over a path extending by way of the first contact of the set 102 and the wiper 104 to the conductor 9. Since the odd numbered contacts of the set 102 are all multiplied together and connected to the negative terminal of the battery 118, it will be apparent that the path, just traced, is completed each time the wiper 104 is moved into engagement with an odd numbered one of the contacts in the set 102. On the other hand, when the wiper engages an even numbered contact of the set 102, such, for example, as the second contact, the battery 119 is connected across the line conductors 8 and 9 of the line circuit 6, the positive terminal of this battery being connected to the line conductor 9 over a path substantially similar to that traced above and extending from the negative terminal of the battery 118. Since all of the even numbered contacts of the set 102 are multiplied together, positive battery potential is impressed upon the line conductor 9 each time the wiper 104 is moved into engagement with one of its associated even numbered contacts. Thus, during continued operation of the switch 100 voltage pulses of alternate opposite polarity are impressed across the conductors 8 and 9 of the line circuit 6.

With the wiper 104 standing in engagement with any one of its associated odd numbered contacts such that negative battery potential is impressed upon the line conductor 9, the polarized relay 50 provided at the master control station shown in Fig. 2 is energized and assumes its operated position. In a similar manner the relays corresponding to the relay 50 and respectively embodied in the other switching units are also caused to operate. The polarized relay 60 on the other hand, is so poled that it does not operate when the voltage of the battery 118 is impressed between the line conductors 8 and 9. The relay 50, upon operating, opens at its armature 51 a point in the circuit, traced hereinafter, for energizing the heating coil 89 of the thermal relay 71. At its armature 52, the relay 50 completes the prepared branch of the operating circuit for the motor 28. More particularly, when the relay 50 operates, the motor 28 is energized over a circuit extending from one terminal of the alternating current source by way of the conductor 20, the armature 52, the switch springs 44_a and 44_b, the windings of the motor 28 and the conductor 19 to the opposite terminal of the alternating current source. When energized over this circuit the motor 28 operates to drive the shaft 32 through one-half of a revolution from the position illustrated in the drawings at the end of which the follower portion of the spring 44_b drops into the depression 48 and the springs 44_a and 44_b are disengaged to interrupt the above-traced operating circuit for the motor 28. Thus, the operation of the motor 28 is arrested. When the shaft 32 is rotated 180 degrees from the position shown in the drawings, the cam 45 is rotated therewith so that the cam follower portion of the spring 43_b is moved out of the depression 46. As a result the springs 43_a and 43_b are moved into engagement to prepare the second branch of the operating circuit for the motor 28. During the movement of the cam 35, the pawl mechanism associated with the ratchet wheel 30 is actuated by the projection 42_a so that the wipers 25, 26 and 27 of the rotary switch 21 are operated one step from the positions shown in the

drawings or into engagement with their respective associated second contacts.

When the wiper 104 of the switch 100 is stepped from engagement with its associated first contact and into engagement with its associated second contact in the manner explained above, the voltage pulse impressed across the line conductors 8 and 9 and derived from the source 118 is terminated, and a voltage pulse of opposite polarity and derived from the source 119 is impressed upon the indicated line conductors. As a consequence, the polarized relay 50 is caused to restore and the polarized relay 60 is caused to operate. Similarly, the relays corresponding to the relay 50 and respectively embodied in the other switching units associated with the line circuit 6 are caused to restore and the relays corresponding to the relay 60 are caused to operate. Upon restoring, the relay 50 reprepares, at its armature 51, the circuit for energizing the heating element 89 of the thermal relay 77 and opens, at its armature 52, a further point in the above-traced branch of the operating circuit for the motor 28. The relay 60, upon operating, opens, at its armature 61, a second point in the circuit for energizing the heating element 89 of the thermal relay 77 and completes, at its armature 62, the second branch of the operating circuit for the motor 28. More particularly, when the relay 60 operates, the motor 28 is energized over a circuit which may be traced as extending from one terminal of the alternating current source by way of the conductor 20, the armature 62, the switch springs 43a and 43b, the windings of the motor 28 and the conductor 19 to the opposite terminal of the alternating current source. When energized over this circuit, the motor 28 again operates to drive the shaft 32 another one-half revolution or back to the position illustrated in the drawings, at which time the cam follower portion of the spring 43b drops into the depression 46 of the cam 45 and the springs 43a and 43b are disengaged. Thus, the operating circuit for the motor 28 is again interrupted and the operation of the motor is arrested. With the shaft 32 and the cams carried thereby occupying the positions illustrated, it will be observed that the camming projection of the spring 44b is moved out of the depression 48 of the cam 47 so that the springs 44a and 44b are closed to reprepare the originally traced branch of the operating circuit for the motor 28. During the one-half revolution traversed by the shaft 32, the projection 42b of the cam 30 engages the lever 38 to actuate the pawl mechanism associated with the ratchet wheel 30, so that the ratchet wheel is operated a second step and the wipers of the switch 21 are advanced into engagement with their respective associated third contacts.

From the foregoing description it will be obvious that the motor 28 is repeatedly energized in response to the alternate operation of the two polarized relays 50 and 60 resulting from the voltage pulses of alternate opposite polarity impressed across the conductors 8 and 9 of the line circuit 6. In this regard, it is pointed out that the duration of the voltage pulses impressed across the line conductors 8 and 9 must be sufficient to permit the motor 28 to drive the shaft 32 through one-half of a revolution each time the motor is energized. With the arrangement shown, it is contemplated that approximately one second shall be required for the motor 28 to drive the shaft 32 one-half of a revolution.

This means, of course, that each voltage pulse impressed across the line conductors 8 and 9 must endure for a time interval slightly greater than one second. Preferably, the duration of each voltage pulse is more than two seconds. It will also be apparent that each time the motor 28 is energized the wipers 25, 26 and 27 of the rotary switch 21 are operated one step. Thus, the wipers of the switch 21, under normal circumstances, operate in synchronism with the wipers of the switch 100 provided at the master control station.

With the switch 32 occupying its normal position, as illustrated in the drawings, the red signal lamp 16 for giving a stop traffic indication to traffic proceeding along the highway 12 and the green signal lamp 14 for giving a right of way traffic indication to traffic proceeding along the highway 11 are energized during the interval when the wipers of the switch 21 are traversing the first twelve contacts of their respective associated contact sets. More particularly, the two indicated signal lamps are energized over a circuit which may be traced as extending from one terminal of the alternating current source by way of the conductor 20, the armature 71 and its associated resting contact, the wiper 25 and the multiplied first to twelfth contacts of the contact set 22 to the conductor 67, where it divides, one branch extending by way of the lamp 16 and the conductor 19 to the opposite terminal of the current source and the other branch extending by way of the lamp 14 and the conductor 19 to the opposite terminal of the current source. During the interval when the wipers of the switch 21 are traversing their respective eleventh and twelfth contacts, the amber signal lamp 15 which serves to give a caution traffic indication to traffic proceeding along the highway 11 is also energized, the circuit for energizing this lamp extending from one terminal of the alternating current source by way of the conductor 20, the wiper 26, the multiplied eleventh and twelfth contacts of the contact set 23, the switch springs 88 and 87, the conductor 65, the lamp 15 and the conductor 19 to the opposite terminal of the current source. Thus, during the change-over period just preceding the transfer of traffic right of way from the highway 11 to the highway 12, the amber or caution signal lamp 15 is energized concurrently with the green signal lamp 14. When the wipers of the switch 21 are moved out of engagement with their respective associated twelfth contacts and into engagement with their respective associated thirteenth contacts, traffic right of way is transferred from the highway 11 to the highway 12 and the caution signal lamp 15 is deenergized. More particularly, the above-traced circuit for energizing the two lamps 14 and 16 is interrupted at the wiper 25 and its associated twelfth contact. Similarly, the above-traced circuit for energizing the amber lamp 15 is interrupted at the wiper 26 and its associated twelfth contact. During the period when the wipers of the switch 21 are traversing their associated contacts numbered from thirteen to twenty-four, the red signal lamp 13 is energized to display a stop traffic indication to traffic proceeding along the highway 11 and the green signal lamp 17 is energized to display a right of way traffic indication to traffic proceeding along the highway 12. The circuit for energizing the lamps 13 and 17 may be traced as extending from one terminal of the alternating current source by way of the conductor 20, the armature 71 and

its associated resting contact, the wiper 25, the multiplied thirteenth to twenty-fourth contacts of the contact set 22, the conductor 66, the lamps 17 and 13 in parallel and the conductor 19 to the opposite terminal of the current source. During the interval when the wipers of the switch 21 are traversing their respective associated twenty-third and twenty-fourth contacts, the amber signal lamp 18 is energized to display a caution traffic indication to traffic proceeding along the highway 12. The circuit for energizing this amber lamp may be traced as extending from one terminal of the alternating current source by way of the conductor 20, the wiper 26, the multiplied twenty-third and twenty-fourth contacts of the contact set 23, the conductor 68, the lamp 18 and the conductor 19 to the opposite terminal of the current source. Thus, the amber lamp 18 is energized concurrently with the green lamp 17 to indicate to traffic proceeding along the highway 12 that a transfer of right of way to the highway 11 is about to be effected. This transfer of right of way is effected and a new signaling cycle started when the wipers of the switch 21 are moved out of engagement with their respective twenty-fourth contacts and into engagement with their respective associated first contacts. Thus, when the wiper 25 is disengaged from its associated twenty-fourth contact and is moved into engagement with its associated first contact, the above-traced circuit for energizing the signaling lamps 13 and 17 is interrupted and the previously traced circuit for energizing the lamps 14 and 16 is again completed. Also, when the wiper 26 is moved out of engagement with its associated twenty-fourth contact, the above-traced circuit for energizing the amber lamp 18 is interrupted. During continued movement of the wipers embodied in the switch 21, the cycle of operations just described is repeated so that traffic right of way is alternately given to the two intersecting highways 11 and 12.

As indicated previously, the manually operable switch 82 is provided for the purpose of changing the percentage of each signaling cycle during which traffic right of way is allotted to the two highways 11 and 12. Thus, with the switch 82 occupying its normal position, as illustrated in the drawings, the eleventh and twelfth contacts of the contact set 22 are multiplied through the springs 83 and 84 of the switch 82 to the permanently multiplied first to tenth contacts of the contact set 22. Hence, the green lamp 14 and the red lamp 16 are held energized to give traffic right of way to the highway 11, during the interval when the wipers of the switch 21 are traversing the first twelve contacts of their respective associated contact sets. With the switch 82 in this position, the switch springs 87 and 88 are also engaged so that the amber lamp 15 is only energized when the wipers of the switch 21 are traversing their respective associated eleventh and twelfth contacts. If, however, the switch 82 is operated to its off-normal position, the springs 83 and 84 are disengaged and the springs 83 and 85 are moved into engagement. Through this operation the eleventh and twelfth contacts of the set 22 are disconnected from the permanently multiplied contacts numbered from one to ten in the contact set 22 and are connected to the permanently multiplied contacts numbered from thirteen to twenty-four in the same contact set. As a result and during movement of the wipers embodied in the switch 21, the period of each signaling cycle during which traffic right of way

is given to the highway 11 is terminated when the wiper 25 is moved out of engagement with its associated tenth contact, whereas the period of each signaling cycle during which traffic right of way is given to traffic proceeding along the highway 12 is increased to include the time interval when the wipers of the switch 21 are traversing their associated eleventh and twelfth contacts. When the switch 82 is operated to its off-normal position the contact spring 87 is moved out of engagement with its associated spring 88 and into engagement with the contact spring 86. As a result, the multiplied ninth and tenth contacts of the contact set 23 are included in the previously traced operating circuit for the amber or caution signal lamp 15 rather than the multiplied eleventh and twelfth contacts of this contact set. Hence, the change-over period, during which the amber lamp 15 is energized, is advanced in each signaling cycle to coincide with the last part of the portion of each signaling cycle during which traffic right of way is given to traffic proceeding along the highway 11.

From the foregoing description it will be apparent that the switch 21 is synchronously operated with the cycle control switch 100 located at the master control station. Specifically, each time the wipers of the switch 100 are stepped one step, the wipers of the switch 21 are likewise stepped one step. It is possible that the synchronous relation between the operating cycles of the two switches may be disturbed and in order to correct any such non-synchronous relation provisions are made for bringing the operated positions of the wipers into coincidence at the end of each operating cycle of the switch 100. To this end a circuit is provided for energizing the polarized relay 80 each time the switch wiper 105 is driven into engagement with its associated first contact. This circuit may be traced as extending from the positive terminal of the battery 119 by way of the wiper 105 and its associated first contact, the switch springs 115 and 116, the line conductor 7, the series connected windings of the relays 70 and 80 and the line conductor 8 to the grounded terminal of the battery 119. In a similar manner current is caused to flow through the windings of the relays corresponding to the relays 70 and 80 and embodied in the other switching units associated with the line circuit 6. The direction of current flow through the winding of the relay 70 and through the respective windings of the other corresponding relays is such that these relays do not operate. The polarized relay 80 and the other corresponding relays, on the other hand, are caused to operate when energized from the battery 119 over the line circuit 6. Upon operating, the relay 80 functions to complete the previously referred to third branch of the operating circuit for the motor 28, provided the switch 21 is out of synchronism with the switch 100. More particularly under these circumstances the motor 28 is energized over a circuit extending from one terminal of the alternating current source by way of the conductor 20, the armature 81, the wiper 27, the multiplied second to twenty-fourth contacts of the set 24, the windings of the motor 28 and the conductor 19 to the opposite terminal of the alternating current source. As a result, the motor 28 operates to drive the wipers of the switch 21 until they are moved into engagement with their respective associated first contacts at which time the above-traced operating circuit for the motor 28 is interrupted at the wiper 27. Obviously, if

the switch 21 is operating in synchronism with the switch 100, the operation of the relay 80 is without effect. It will further be apparent that, when the wiper 105 is moved out of engagement with its associated first contact, the above-traced circuit for energizing the polarized relay 80 and the other relays corresponding thereto is interrupted causing all of these relays to restore. Upon restoring, the relay 80 opens, at its armature 81, a further point in the above-traced operating circuit for the motor 28.

It is pointed out that the period during which the relay 80 is held energized at the beginning of each operating cycle is sufficient to permit the motor 28 to drive the wipers 25, 26 and 27 over a substantial portion of the contact points embodied in the switch 21. It is further pointed out that coincident positions of the wipers respectively embodied in the respective rotary switches of the various switching units may not necessarily represent the desired synchronous relation between the rotary switch operating cycles. For example, if the so-called progressive type of traffic control is utilized, the operating cycles of the switches corresponding to and including the switch 21 are so related that the signaling cycles are started successively and at different time intervals at succeeding intersections along the controlled highway. To this end different ones of the contacts in the contact sets, corresponding to the contact set 24 of the switch 21, but provided in the rotary switches of the other switching units controlled over the line circuit 6 may be left unwired. Thus, if four phase progressive traffic control is desired for traffic traveling east along the highway 11, the nineteenth contact of the set corresponding to the contact set 24 in the rotary switch of the unit located immediately east of the intersection 10 will be left unwired, all other contacts of this set being multiplied together. In this assumed case, the thirteenth contact of the contact set corresponding to the set 24 and embodied in the rotary switch of the switching unit located at the intersection two intersections removed in an eastward direction along the highway 11 from the intersection 10 would be left unwired and all other contacts thereof would be multiplied together. Finally, in the assumed case the seventh contact of the contact set corresponding to the set 24 and embodied in the rotary switch of the switching unit located at the intersection three intersections removed in an eastward direction along the highway 11 from the intersection 10 would be left unwired and all other contacts thereof would be multiplied together. Thus, by proper selection of the unwired contacts in the respective contact sets corresponding to the contact set 24 but embodied in others of the switching units any desired type of progressive traffic control may be achieved. In such case even though the signaling cycles of the various intersections are displaced in phase, the operating cycles of the rotary switches respectively embodied in the switching units and corresponding to the switch 21 are synchronous and the synchronous relation therebetween is maintained through the provision of the apparatus just described.

As previously indicated, operation of the manually operable switch including the contact springs 109, 110 and 111 is effective to change the time interval of each signaling cycle. More particularly, with the enumerated contact springs occupying the positions illustrated, the operating magnet 106 of the switch 100 is energized in

accordance with the pulses of slow rate impressed upon the conductor 108 by the pulse generator 101. When, however, the movable spring 109 is operated out of engagement with the spring 111 and into engagement with the spring 110, the magnet 106 is connected to be energized in accordance with the pulses of fast rate impressed upon the conductor 107 by the generator 101, with the result that the time interval of each signaling cycle is materially reduced. If desired, a clock driven circuit changer may be used in lieu of the manually operable switch, this circuit changer being operative to connect the magnet 106 to be energized in accordance with the pulses of slow rate during certain periods of the day when heavy traffic conditions exist, and to connect the magnet 106 to be energized in accordance with pulses of fast rate during the remaining portions of the day when light traffic conditions exist.

As pointed out previously, the switch 112 provided at the master control station is utilized for the purpose of interrupting the normal cyclic operation of the switching units associated with the line circuit 6 and causing the caution signaling devices provided at the respective controlled intersections to be energized to display caution signals to traffic proceeding in all traffic approach directions. More particularly, when the switch 112 is operated to its off-normal position the springs 114 are disengaged to open the previously traced circuit by way of which the rotary switch operating magnet 106 is energized in accordance with the pulse output of the pulse generator 101. Thus, operation of the switch 100 is arrested. When the operation of the switch 100 is arrested, voltage pulses of alternate opposite polarity are no longer impressed across the conductors 8 and 9 of the line circuit 6 and hence operation of the switch 21 and of the other similar switches respectively embodied in the other switching units associated with the line circuit 6 is arrested. It is noted, however, that operation of the switch 112 is ineffective to remove the voltage of one of the two current sources 118 and 119 from across the indicated line conductors. Thus, if the switch 112 is operated to its off-normal position immediately after the wipers 104 of the switch 100 has been operated into engagement with an even numbered contact the voltage of the current source 119 is maintained on the line conductors 8 and 9 and the relay 60 is held operated. By virtue of this arrangement operation of the motor 28 to drive the shaft 32 through a full half of a revolution is insured even though the switch 112 is operated to its off-normal position immediately after the motor 28 starts to operate. Hence, the possibility of the switch 100 being operated one step ahead of the switches corresponding to and including the switch 21 is obviated. When the switch 112 is operated to its off-normal position, a point is opened, at the springs 115 and 116, in the previously traced path by way of which the synchronizing voltage pulses are impressed between the line conductors 7 and 8 of the line circuit 6. At the springs 116 and 117, an obvious path is completed for impressing the voltage of the current source 118 across the conductors 7 and 8 of the line circuit 6, the negative terminal of the current source 118 being connected to the line conductor 7. When voltage of this polarity is impressed between the line conductors 7 and 8, the polarized relay 76 of the switching unit illustrated in Fig. 2 is energized and operates. Similarly, the relays corresponding to the relay 70

and respectively embodied in the other switching units also operate. On the other hand, the relay 80 and the other corresponding relays are so poled that they do not operate when voltage of the polarity indicated is impressed across the line conductors 7 and 8. Upon operating, the relay 70 opens, at the armature 71 and its associated resting contact, a point in the circuit, traced hereinafter, for energizing the heating element 89 of the thermal relay 77. At the armature 71 and its associated resting contact, a point is also opened in the common portion of the previously traced circuits for energizing the signal lamps 13, 14, 16 and 17, thereby to deenergize the two of these lamps which are energized at the time 15 the switch 112 is operated to its off-normal position. At the armature 71 and its associated working contact, the relay 70 completes a circuit for energizing the amber signal lamp 18, which circuit may be traced as extending from one terminal of the alternating current source by way of the conductor 20, the armature 71, the conductor 68, the lamp 18 and the conductor 19 to the opposite terminal of the current source. At its armature 72, the relay 70 completes a circuit for energizing the amber signal lamp 15, this circuit extending from one terminal of the alternating current source by way of the conductor 20, the armature 72, the conductor 65, the lamp 15 and the conductor 19 to the opposite terminal of the current source. Thus, any energized ones of the lamps 13, 14, 16 and 17 are deenergized and the amber signal lamps 15 and 18 are both energized. The last-mentioned lamps are maintained energized until the switch 112 is restored to 35 normal to open the above-traced circuit for energizing the polarized relay 70. Obviously, when the switch 112 is returned to its normal position, the springs 116 and 117 are disengaged to open the above-traced circuit for energizing the relay 70 and the other relays corresponding thereto. As a result, the relay 70 restores to open, at its armatures 71 and 72, the above-traced circuits for energizing the amber lamps 18 and 15, respectively. At the armature 71 and its associated resting contact, the circuit for energizing the heating element 89 of the thermal relay 77 is re-prepared and one of the circuits for energizing the signal lamps 14 and 16 or the lamps 13 and 17 is recompleted. When the switch 112 is re-turned to its normal position, the cyclic operation of the rotary switch 100 is resumed with the result that voltage pulses of alternate opposite polarity are again impressed across the line conductors 8 and 9 of the line circuit 6 and the cyclic operation of the switch 21 is again initiated.

Referring now more particularly to the operation of the auxiliary control apparatus 75, it will be recalled from the preceding description that during the normal operation of the apparatus embodied in the switching unit illustrated in Fig. 2, the operating circuit for the thermal relay 77 is interrupted at one of the three armatures 51, 61 and 71. If, for some reason, a fault occurs in the system such that both of the polarized relays 50 and 60 are deenergized at a time when they should be operating alternately to complete the two previously traced branches of the operating circuit for the motor 28, the above mentioned circuit for energizing the heating element 89 of the thermal relay 77 is completed. This circuit may be traced as extending from one terminal of the alternating current source by way of the conductor 20, the armature 71 and its associated

resting contact, the armatures 61 and 51, the heating coil 89 and the conductor 19 to the opposite terminal of the current source. When energized over this circuit, the heating coil 89 delivers 5 heat energy to the bimetallic strip 78 with the result that this strip is flexed to the left from the position illustrated in the drawings. After a predetermined time interval the strip 78 is moved into engagement with the contact 79, thereby to 10 complete the operating circuit for the motor 28. The last-mentioned circuit extends from one terminal of the alternating current source by way of the conductor 20, the armatures 71, 61 and 51, the bimetallic strip 78, the contact 79, the windings of the motor 28 and the conductor 19 to the opposite terminal of the current source. When energized over this circuit, operation of the motor 28 is initiated and this motor functions to drive the shaft 91 through the speed reducing gear mechanism of the gear box 92. As the two cams 95 and 99 carried by the shaft 91 are rotated, the two branches of the operating circuit for the motor 28 are alternately completed. More particularly, if the cams 95 and 99 are 20 started rotating from the positions illustrated in the drawings, the branch of the operating circuit for the motor 28 which includes the springs 44a and 44b is held prepared at the springs 94 and 97 of the switch 92. After the cams 95 and 99 have been rotated approximately 150 degrees from the positions shown in the drawings, the cam 99 moves the spring 98 into engagement with the associated contact springs 63 and 64 to complete the last-mentioned branch of the operating circuit for the motor 28. This circuit may be traced as extending from one terminal of the alternating current source by way of the conductor 20, the armatures 71, 61 and 51, the bimetallic strip 78, the contact 79, the contacts 64, 98, 63, 94 and 97, the contact springs 44a and 44b, the windings of the motor 28 and the conductor 19 to the opposite terminal of the current source. When energized over this circuit, the motor 28 operates in the manner previously explained to 30 drive the shaft 32 through an angle of 180 degrees at which time the cam follower portion of the spring 44b drops into the depression 48 of the cam 47 to open, at the springs 44a and 44b, the branch circuit just traced. During the one-half revolution imparted to the shaft 32, the wipers of the rotary switch 21 are advanced one step in the manner previously described. Shortly following the operation of the shaft 32 to its new angular position, the cams 95 and 99 are moved to a point where the cam follower portions of the springs 94 and 98 engage the peripheral surfaces of the two cams 95 and 99, respectively, of reduced radius. During this movement of the cam 95, the spring 94 is moved out of engagement with the spring 97 to open a further point in the above-traced branch of the operating circuit for the motor 28 and into engagement with the spring 96 to prepare the branch of the operating circuit for the motor 28 which includes the springs 43a and 43b. The cam follower portion of the spring 98 drops onto the portion of the cam 99 of reduced radius shortly before the spring 94 is moved into engagement with the spring 96. When this occurs the spring 98 is moved out of 40 engagement with its associated contacts 63 and 64 to open further points in the above-traced branch of the operating circuit for the motor 28. During continued rotary movement of the shaft 91, the cam 99 again moves the spring 98 into engagement with its associated contact springs 50 45 55 60 65 70 75

63 and 64, thereby to complete the second branch of the operating circuit for the motor 28. This second branch circuit may be traced as extending from one terminal of the alternating current source by way of the conductor 20, the armatures 71, 61 and 51, the bimetallic strip 78, the contact 79, the springs 64, 98, 63, 94, 96, 43a and 43b, the windings of the motor 28 and the conductor 19 to the opposite terminal of the current source. When energized over this circuit the motor 28 again operates to drive the shaft 32 through another one-half revolution, thereby to cause the wipers of the switch 21 to be advanced an additional step. When the last-mentioned half revolution of the shaft 32 is completed, the cam follower portion of the spring 43b drops into the depression 46 of the cam 45 to open, at the springs 43a and 43b, the second branch of the operating circuit for the motor 28, thereby to arrest the operation of this motor. Also, at the springs 44a and 44b, the first-traced branch of the operating circuit for the motor 28 is again prepared. Shortly following the last-described operation on the part of the motor 28, the enlarged portion of the cam 95 moves the spring 94 out of engagement with the spring 96 and into engagement with the spring 97. Shortly before the spring 94 is moved into engagement with the spring 96, the cam follower portion of the spring 98 drops onto the portion of the cam 99 of reduced radius so that this spring is moved out of engagement with the contact springs 63 and 64. Thus, the first branch of the operating circuit for the motor 28 is again prepared at the contact springs 44a, 44b, 94 and 97 and is held open at the springs 63, 64 and 98 of the switch 93 until the shaft 91 is driven through an additional 150 degrees. From the foregoing description it will be apparent that so long as the motor 76 continues to operate, the two cam controlled switches 92 and 93 function alternately to complete the two branches of the operating circuit for the motor 28 with the result that the wipers of the switch 21 are driven over the contacts of their associated contact sets and the cyclic energization of the signaling devices 13 to 18, inclusive, is continued. Thus, the provision of the auxiliary control means 75 prevents the traffic control from being disrupted.

If, following operation of the auxiliary control apparatus 75 in the manner just explained, the normal alternate operation of the relays 50 and 60 is resumed, the operation of the auxiliary control apparatus is arrested and the motor 28 is again controlled through the alternate operation of the two polarized relays. More particularly, when either of the two relays 50 and 60 is caused to operate, a point is opened, at one of the two armatures 51 and 61, in the common portion of the two branches of the operating circuit for the motor 28, the operating circuit for the motor 76, and the previously traced circuit for energizing the heating element 89 of the thermal relay 77. Also, during continued alternate operation of the two relays 50 and 60, the armatures 51 and 61 are alternately effective to maintain the common portion of the indicated circuits open. Thus, the operation of the motor 76 is arrested, the heating coil is deenergized and the bimetallic strip 78 assumes its unflexed position out of engagement with the contact 79. With the strip 78 disengaged from the contact 79, a further point is opened in the common portion of the operating circuit for the motor 76 and the two previously traced branches of the

operating circuit for the motor 28. Thus, the operation of the auxiliary control apparatus is arrested and the motor 28 is controlled in the normal manner as previously explained.

5 The arrangement of the system is such that if the polarized relay 70 operates at a time when the auxiliary control apparatus 75 is operating the operation of this apparatus is arrested, the operation of the switch 21 is arrested, and the 10 cyclic energization of the signaling devices provided at the intersection 10 is discontinued. Thus, the relays 50 and 60 may, due to a fault in the line conductor 9, for example, be rendered nonresponsive to voltage pulses impressed 15 across the conductors 8 and 9, without affecting the circuit for energizing the polarized relays 70 and 80. In this case, if the manually operable switch 112 provided at the master control station is operated to its off-normal position to cause the 20 operation of the relay 70 in the manner previously explained, the relay 70 functions to open, at its armature 71 and the associated resting contact, a point in the common portion of the two previously traced branch circuits for energizing the motor 28. At this same armature and its associated resting contact, a point is also opened in the common portion of above-traced circuit for energizing the heating coil 89 of the thermal relay 77 and the previously traced circuit 25 for energizing the motor 76. Thus, the operation of the auxiliary control apparatus 75 and of the stepping switch 21 is arrested. Operation of the relay 70 also results in the deenergization of any energized ones of the lamps 13, 14, 30 15 and 17 and the energization of the amber signal lamps 15 and 18 in the manner previously explained. Obviously, if the relay 70 is deenergized subsequent to its energization and before the fault responsible for the dormant condition 35 of the two polarized relays 50 and 60 is cleared, operation of the auxiliary control apparatus 75 is resumed to again initiate the cyclic energization of the signaling devices provided at the intersection 10. In any case when the operation of the auxiliary control apparatus 75 is arrested and the normal operation of the switching apparatus embodied in the switching unit illustrated in 40 Fig. 2 is resumed, the previously described synchronizing means functions to bring the operating 45 cycles of the various switching units into synchronism.

50 While there has been described what is at present considered to be the preferred embodiment of the invention, it will be understood that 55 various modifications may be made therein, and it is intended to cover in the appended claims all such modifications as fall within the true spirit and scope of the invention.

What is claimed is:

60 1. A traffic signaling switching unit adapted to be controlled by way of a line circuit connected thereto and operative to energize a plurality of traffic signaling devices in a definite cyclic order, said unit comprising, in combination, a switch including contacts, a wiper associated with said contacts and motor means for driving said wiper over said contacts, means including circuit connections controlled by the movement of said wiper over said contacts for 65 energizing said signaling devices in said definite cyclic order, an operating circuit for said motor means, a pair of polarized relays alternately operative in response to voltage pulses of alternate opposite polarity impressed on said line circuit, means including said relays for repeatedly com-

pleting said operating circuit, thereby to cause said motor means to drive said wiper over said contacts, normally inactive auxiliary control means also operative repeatedly to complete said operating circuit, and means responsive to a sustained deenergized condition of both of said relays for initiating the operation of said auxiliary control means.

2. A traffic signaling switching unit adapted to be controlled by way of a line circuit connected thereto and operative to energize a plurality of traffic signaling devices in a definite cyclic order, said unit comprising, in combination, a switch including contacts, a wiper associated with said contacts and motor means for driving said wiper over said contacts, means including circuit connections controlled by the movement of said wiper over said contacts for energizing said signaling devices in said definite cyclic order, an operating circuit for said motor means, a circuit controlling device adapted to be energized by control voltage impressed on said line circuit, means including said circuit controlling device for completing said operating circuit, thereby to cause said motor means to drive said wiper over said contacts, auxiliary switching means for completing said operating circuit, auxiliary motor means for actuating said auxiliary switching means, an operating circuit for said auxiliary motor means, and means including said circuit controlling device for completing said last-mentioned operating circuit when said circuit controlling device remains deenergized for a sustained time interval.

3. A traffic signaling switching unit adapted to be controlled by way of a line circuit connected thereto and operative to energize a plurality of traffic signaling devices in a definite cyclic order, said unit comprising, in combination, a switch including contacts, a wiper associated with said contacts and motor means for driving said wiper over said contacts, means including circuit connections controlled by the movement of said wiper over said contacts for energizing said signaling devices in said definite cyclic order, an operating circuit for said motor means, a circuit controlling device adapted to be energized by control voltage impressed on said line circuit, means including said circuit controlling device for completing said operating circuit, thereby to cause said motor means to drive said wiper over said contacts, auxiliary switching means for completing said operating circuit, auxiliary motor means for actuating said auxiliary switching means, an operating circuit for said auxiliary motor means, said circuit controlling device being operative, when deenergized, to prepare said last-mentioned operating circuit, and means comprising a thermal relay operative in response to sustained deenergization of said circuit controlling device for completing said last-mentioned operating circuit.

4. A traffic signaling switching unit adapted to be controlled by way of a line circuit connected thereto and operative to energize a plurality of associated traffic control signaling devices in a definite cyclic order, said unit comprising, in combination, a switch including contacts, a wiper associated with said contacts and motor means for driving said wiper over said contacts, means including circuit connections controlled by the movement of said wiper over said contacts for energizing said signaling devices in said definite cyclic order, a pair of polarized relays including windings adapted to be connected to said line

circuit, said windings being so poled that one of said relays responds to voltage pulses of one polarity impressed on said line circuit and the other of said relays responds to voltage pulses of opposite polarity impressed on said line circuit, an operating circuit for said motor means, said circuit comprising two branches each including a switch controlled by said motor means, said circuit branches being so connected and arranged that one thereof is completed upon operation of one of said relays and is opened by the motor controlled switch included therein when said wiper is operated through a predetermined movement and the other thereof is prepared at the end of said predetermined movement, is completed upon operation of the other of said relays and is opened by the motor controlled switch included therein when said wiper is operated through a second predetermined movement, normally inactive auxiliary control means comprising a motor and switches individually included in said branches of said operating circuit, said auxiliary control means being operative alternately to complete said branches of said operating circuit in the same order as said relays when said motor is operating, and means responsive to sustained deenergization of said relays for initiating the operation of said motor.

5. A traffic signaling switching unit adapted to be controlled by way of a line circuit connected thereto and operative to energize a plurality of associated traffic control signaling devices in a definite cyclic order, said unit comprising, in combination, a switch including contacts, a wiper associated with said contacts and motor means for driving said wiper over said contacts, means including circuit connections controlled by the movement of said wiper over said contacts for energizing said signaling devices in said definite cyclic order, a pair of polarized relays including windings adapted to be connected to said line circuit, said windings being so poled that one of said relays responds to voltage pulses of one polarity impressed on said line circuit and the other of said relays responds to voltage pulses of opposite polarity impressed on said line circuit, an operating circuit for said motor means, said circuit comprising two branches each including a switch controlled by said motor means, said circuit branches being so connected and arranged that one thereof is completed upon operation of one of said relays and is opened by the motor controlled switch included therein when said wiper is operated through a predetermined movement and the other thereof is prepared at the end of said predetermined movement, is completed upon operation of the other of said relays and is opened by the motor controlled switch included therein when said wiper is operated through a second predetermined movement, normally inactive auxiliary control means comprising a motor and switches individually included in said branches of said operating circuit, said auxiliary control means being operative alternately to complete said branches of said operating circuit in the same order as said relays when said motor is operating, an operating circuit for said motor, said relays being operative, when deenergized to prepare said last-mentioned operating circuit, and means comprising a thermal relay operative in response to sustained deenergization of said relays for completing said last-mentioned operating circuit.

6. A traffic signaling switching unit adapted to be controlled by way of a line circuit connect-

ed thereto and operative to energize a plurality of associated traffic control signaling devices in a definite cyclic order, said unit comprising, in combination, apparatus normally operative in response to control voltage of one character impressed on said line circuit for causing the energization of said signaling devices in said definite cyclic order, normally inactive auxiliary control means for causing said apparatus to operate, means operative in the absence of said control voltage on said line circuit for initiating the operation of said auxiliary control means, and means operative to arrest the operation of said auxiliary control means in response to a control voltage of different character impressed on said line circuit.

7. A traffic signaling switching unit adapted to be controlled by way of a line circuit connected thereto and operative to energize a plurality of associated traffic control signaling devices in a definite cyclic order, said unit comprising, in combination, apparatus normally operative in response to control voltage of one character impressed on said line circuit for causing the energization of said signaling devices in said definite cyclic order, normally inactive auxiliary control means for causing said apparatus to operate, means operative in the absence of said control voltage on said line circuit for initiating the operation of said auxiliary control means, and means operative in response to a control voltage of different character impressed on said line circuit for causing the energization of a predetermined one of said signaling devices and for arresting the operation of said auxiliary control means in the event said auxiliary control means is operating at the time said control voltage of different character is impressed on said line circuit.

8. A traffic signaling switching unit adapted to be controlled by way of a line circuit connected thereto and operative to energize a plurality of traffic control signaling devices in a definite cyclic order, said unit comprising, in combination, a switch including contacts, a wiper associated with said contacts and motor means for driving said wiper over said contacts, means including circuit connections controlled by the movement of said wiper over said contacts for energizing said signaling devices in said definite cyclic order, control means responsive to control voltage of one character impressed on said line circuit for normally controlling the operation of said motor means, normally inactive aux-

iliary control means for controlling the operation of said motor means, means responsive to an inactive condition of said first-mentioned control means for initiating the operation of said auxiliary control means, and means operative to arrest the operation of said auxiliary control means in response to a control voltage of different character impressed on said line circuit.

9. A traffic signaling switching unit adapted to be controlled by way of a line circuit connected thereto and operative to energize a plurality of traffic signaling devices in a definite cyclic order, said unit comprising, in combination, means including pulse controlled switching apparatus for energizing said signaling devices in said definite cyclic order, a pair of polarized relays alternately operative in response to voltage pulses of alternate opposite polarity impressed on said line circuit, means controlled in accordance with the alternate operation of said relays for transmitting current pulses to said switching apparatus, thereby to cause the operation of said apparatus, auxiliary control means also operative to transmit current pulses to said switching apparatus, said auxiliary control means normally being ineffective to transmit current pulses to said switching apparatus, and means responsive to a sustained deenergized condition of at least one of said relays for rendering said auxiliary control means effective to transmit current pulses to said switching apparatus.

10. A traffic signaling switching unit adapted to be controlled by way of a line circuit connected thereto and operative to energize a plurality of traffic signaling devices in a definite cyclic order, said unit comprising, in combination, apparatus normally operative in response to control voltage of one character impressed on said line circuit for causing the energization of said signaling devices in said definite cyclic order, auxiliary control means also operative to cause the operation of said apparatus, said auxiliary control means normally being ineffective to cause the operation of said apparatus, means operative in response to the absence of said control voltage on said line circuit for rendering said auxiliary control means effective to cause the operation of said apparatus, and means operative in response to a control voltage of different character impressed on said line circuit for rendering said auxiliary control means ineffective to cause the operation of said apparatus.
